[57] CLAIM

The ornamental design for a optical scanner, as shown
and described.

DESCRIPTION

FIG. 1 is a top, front, left side perspective view of an
optical scanner showing our new design;

FIG. 2 is an enlarged top plan view thereof;

FIG. 3 is an enlarged front elevational view thereof;

FIG. 4 is an enlarged left side elevational view thereof;

FIG. 5 is an enlarged right side elevational view
thereof;

FIG. 6 is an enlarged rear elevational view thereof; and,

FIG. 7 is an enlarged bottom plan view thereof.

FIG. 1

FIG. 2

FIG. 3

FIG. 5

FIG. 4

FIG. 6

FIG. 7
